[57] CLAIM

The ornamental design for a holder for character sign set elements, as shown and described.

DESCRIPTION

FIG. 1 is front elevational view of a holder for character sign set elements according to the present invention showing my new design;

FIG. 2 is a rear elemental view thereof;

FIG. 3 is a top plan view thereof, with the bottom view being a mirror image;

FIG. 4 is a sectional view taken along line 4—4 of FIG. 2;

FIG. 5 is a left side elevational view thereof;

FIG. 6 is a right side elevational view thereof;

FIG. 7 is a right side elevational view of a second embodiment thereof;

FIG. 8 is a front elevational view thereof; and,

FIG. 9 is a sectional view taken along line 9—9 of FIG. 8.

FIG. 1

FIG. 2

FIG. 3
